US0D1064274S

(12) **United States Design Patent** (10) Patent No.: **US D1,064,274 S**
(45) Date of Patent: ** Feb. 25, 2025

(54) **IMAGER**

(71) Applicant: **GE Healthcare Bio-Sciences AB**, Uppsala (SE)

(72) Inventors: **Thiyaga Rajan**, Bengaluru Karnataka (IN); **Sowmya Balachandran**, Singapore (SG); **Erik Bjerneld**, Uppsala (SE)

(73) Assignee: **Cytiva Sweden AB**, Uppsala (SE)

(***) Term: **15 Years**

(21) Appl. No.: **29/718,255**

(22) Filed: **Dec. 23, 2019**

(30) **Foreign Application Priority Data**

Jul. 5, 2019 (GB) 6064905

(51) **LOC (15) Cl.** **24-01**

(52) **U.S. Cl.**

USPC **D24/160**

(58) **Field of Classification Search**

USPC D24/158–161, 185–187, 107, 231–234; D10/78, 81, 47

CPC .. A61B 5/05; A61B 5/055; A61B 6/03; A61B 6/035; G01N 2035/00306
